Des. 183,072
Patented June 17, 1958

183,072

DISPENSING UNIT FOR A BEVERAGE CONTAINER OR THE LIKE

Richard K. Wentz, Baltimore, Md.

Application April 9, 1956, Serial No. 40,987

Term of patent 14 years

(Cl. D2—3)

FIG. 1

FIG. 2

FIG. 3

Portions of the tube element are broken away to indicate indeterminate length.

I claim:

The ornamental design for a dispensing unit for a beverage container on the like, as shown and described.
